Francis M. Tanehill INVENTOR.

Richard H. Tanehill ATTORNEY.

UNITED STATES PATENT OFFICE.

FRANCIS M. TANEYHILL, OF BARNESVILLE, OHIO.

CAR-WHEEL.

SPECIFICATION forming part of Letters Patent No. 257,625, dated May 9, 1882.

Application filed December 24, 1881. (Model.)

To all whom it may concern:

Be it known that I, FRANCIS M. TANEYHILL, a citizen of the United States, residing at Barnesville, in the county of Belmont and State of Ohio, have invented new and useful Improvements in the Hubs of Coal-Car Wheels and in the Oil-Boxes to Coal-Car Wheels, of which the following is a specification.

My invention relates to improvements in car-wheels; and it consists in details of construction and arrangement of the several parts that will be hereinlater more fully set forth in the specification and claim, and pointed out in the accompanying drawings, in which—

Figure 1 is a section of a car-wheel embodying my improvements; Fig. 2, a section on line *xx*, Fig. 1; Fig. 3, a section of same on line *bb*, Fig. 4; and Fig. 4 is a side view of the wheel.

Like letters of reference refer to like parts in the several figures.

Referring more particularly to the drawings, *e* represents those parts of the solid hub between the wedge-shaped openings *d*, through and lengthwise the solid hub, by means of which the oil is enabled to pass to the axle, and said openings also serve to hold, lift, and distribute the oil as the wheel revolves.

e represents those parts of the solid hub at the posterior ends of the openings *d*, and are sloped back from the ends of said openings.

At the inside end of the oil-box are the posterior bars, *f*, which act to produce checks or eddies and currents in the oil as the wheel revolves, and also prevent the oil from smearing on the rim and ends of the oil-box, thereby forcing oil to the points of lubrication.

The oil-box is provided with an oil chamber or recess, *G*, in its outer rim, and has an opening, *H*, to the outside end of said oil-chamber. 40 Through this opening *H* the oil box may be filled full of oil without affecting the tightness of the oil-box, thereby increasing the period of lubrication. This opening *H* is hermetically closed by a screw plug and cap, *K*, secured in 45 place by screws and taps *L m*. By means of cap *K* the oil is prevented from wasting, and dust and other foreign substances excluded from the oil-box. The axle *N* is by this construction of wheel kept constantly lubricated 50 with pure oil and wastage prevented.

I am aware that hubs to coal-car wheels have been so constructed as to let the oil to the axle, and that they have been made with unbroken surfaces on the inside of the rim and ends of the oil-box and placed between the hub and inside ends of the spokes of the wheels. Such construction I do not claim; but 55

I do claim—

In a car-wheel provided with a recessed oil-box, the combination of the bars *f* on the inside of said oil-box, a hub having wedge-shaped openings *d* for the passage of the oil to the axle, the solid ends *e* sloping back from the ends of the oil-openings, and a removable cap, 60 *K*, hermetically secured to the outer end of the oil-box, substantially as shown and described, and for the purpose set forth.

FRANCIS M. TANEYHILL.
